UNITED STATES PATENT OFFICE.

ELI J. BLAKE, OF BUFFALO, NEW YORK, ASSIGNOR TO GOULD COUPLER COMPANY,
A CORPORATION OF NEW YORK.

GENERATOR SUSPENSION.

Application filed October 29, 1921. Serial No. 511,373.

To all whom it may concern:

Be it known that I, ELI J. BLAKE, a citizen of the United States, and resident of Buffalo, in the county of Erie and State of New York, have invented certain new and useful Improvements in Generator Suspensions, of which the following is a specification.

The invention relates to improvements in generator suspensions, more particularly for use on railway cars where an electric generator is used for lighting purposes. One of the objects of the invention is to provide a simple and effective arrangement for suspending the generator beneath the body of the car and maintaining the belt by which the generator is driven from the car axle under suitable tension. Other objects of the invention relate to improved combinations of parts and constructional elements and details, all as will be more fully described in the following specification and particularly pointed out in the appended claims.

In order that a clearer understanding of the invention may be had attention is hereby directed to the accompanying drawings forming a part of this application and illustrating one embodiment of the invention.

In the drawings,

Fig. 1 represents a side view of part of a railway car having one form of the invention applied thereto, one member being shown in section;

Fig. 2 is an end view of parts shown in Fig. 1;

Fig. 3 is an enlarged section taken on line 3—3 of Fig. 2;

Fig. 4 is an enlarged section taken on line 4—4 of Fig. 1;

Fig. 5 is a view similar to that shown in Fig. 1 showing a modified form of construction;

Fig. 6 is an end view of parts shown in Fig. 5;

Fig. 7 is an enlarged sectional view taken on line 7—7 of Fig. 6; and

Fig. 8 is a section taken on line 8—8 of Fig. 7.

Referring to Figures 1 to 4 of the drawings, the generator 1 is shown as supported by a pair of support rods 2, 2, from an adapter casting 3 which swings upon a hinge or pivot pin 4 which is mounted in the depending arms of the yoke casting 5. The latter rests upon the channel 6 which is at-

tached to the car body, one of the longitudinal beams of the car body being indicated at 6¹.

The generator 1 is adapted to be driven from a car axle by means of a belt indicated 6⁰ at 7 extending around a suitable pulley 8 secured to the shaft of the generator. It is not deemed necessary to illustrate herein the car axle to which belt 7 extends, the axle, however, being considered as located to the right of the generator as viewed in Fig. 1. During conditions of operation the generator will swing about hinge pin 4 towards and away from the car axle in the well known manner. The yoke 5 may be centered 7⁰ on a bolt 9 and may be aligned with the axle by aligning screws 10 which are threaded through suitable openings in a casting 11 attached to the lower side of the channel 6.

In the construction illustrated the tension 7⁵ spring 12 is provided at its upper end with a hook 13 which is hooked through an eye 14 formed at the lower end of a hook member 15. This hook member may be supported by hanging the same over one of the flanges 8⁰ of the suspension yoke 5, this flange having a notch formed therein in which the hook member 15 rests. The stem portion of hook member 15 projects through suitable openings formed in the webs of yoke 5 and of 8⁵ channel 6.

In the construction illustrated the opposite or lower end of spring 12 is finished as a double hook within which rests a bar 16. A threaded opening extends through bar 16, 9⁰ a comparatively long bolt 17 being threaded through this opening. The bolt 17 also extends loosely through an opening in the flange 18 of the bracket 19 which is secured to the side of the generator, bolt 17 being provided for the purpose of extending spring 12 by drawing bar 16 down toward or against its seat on the flange 18 of bracket 19. The double hook arrangement at the lower end of the spring forms an effective abutment against which bar 16 presses, the details of this arrangement being indicated in Figs. 3 and 4, in which it will be noted that surfaces are provided against which the bar or rod 16 may rest with the hooked end portions of the spring below the same.

It will be noted that with this arrangement the tension spring extends downwardly at a steep angle, greater than 45° to the horizontal, from a connection with the car body 11⁰

to a connection with the generator at the side of the latter away from the car axle by which the generator is driven. Accordingly a substantial component of the force of the 5 spring acts upwardly at all times so as to oppose the weight of the generator to a considerable extent. Accordingly the combined spring and gravity load on the hinge pin 4 is correspondingly reduced.

10 Spring 12 will, of course, at the same time tend to swing the generator around its pivotal support at the hinge pin 4 in the direction away from the car axle. With this arrangement the tension on the belt 15 will remain more or less substantially constant throughout the normal range of movement of the generator as the latter swings back and forth, as the distance between the driving axle and the pivot 4 of the 20 generator varies. As the generator swings towards the axle, the weight of the generator tending to swing back tends to maintain the tension of the belt and the tension of the spring is also somewhat increased, 25 but at the same time the lever arm to the end of which the spring is applied is correspondingly reduced, the lever arm referred to being, of course, the perpendicular distance between the axis of the spring and 30 the axis of the hinge pin 4. Similarly as the generator swings away from the car axle, that is to the left, referring to Fig. 1, the tension of the spring will be somewhat reduced but at the same time the lever arm of the spring will be increased, while the weight of the generator tends to decrease 35 tension on the belt. These various factors may be so related as to maintain more or less approximately constant belt tension, as 40 stated, with the added advantage of causing the upward pull of the spring to decrease the load on the hinge pin 4.

Another feature of the invention consists in the provision of a screw-jack arranged to 45 force the generator forwardly against the action of spring 12 when the belt is to be applied to the pulley 8 on the generator and the corresponding pulley on the car axle.

In the arrangement shown in the drawings the sleeve 20 is pivotally mounted on one of the support rods 2. Sleeve 20 may be properly located longitudinally of the support rod 2 by means of a pipe spacer 21 positioned on rod 2 between sleeve 20 and 55 the opposite supporting arm of casting 3. Sleeve 20 is internally threaded and is adapted to receive a screw 22 which extends out of the upper end of the sleeve and is provided with a rigid hand wheel 23. 60 Screw 22 is provided with an extension 24 of reduced diameter which passes loosely through an opening in channel 6 for the purpose of properly locating and positioning the device. A semi-spherical, loose 65 washer 25 is mounted on the extension 24

of screw 22 and bears against the shoulder at the upper end of the portion of the screw, the diameter of which is not reduced. This semi-spherical washer serves to furnish a bearing against the lower edges of the 70 opening referred to in channel 6, when the screw is screwed upwardly to cause the washer to engage against the underside of channel 6.

The length of the screw 22 up to the end of its portion of full diameter is such as to permit the generator to swing away from the axle the maximum desired distance when the screw is screwed down to its lowest position. When, however, it is desired to apply or renew the belt 7 the screw is screwed upwardly until washer 25 engages against the under surface of channel 6, as stated, after which further upward movement of the screw forces the generator 85 to swing about its pivot 4 toward the car axle, against the resistance of spring 12 and of gravity. After the belt has been renewed, the screw is again turned to its lowest position and thereafter the extension 90 24 merely slides through the hole in the channel as the generator swings back and forth until the next occasion for renewing the belt.

The construction shown in Figs. 5 to 8 95 inclusive may be substantially the same as that previously described except in regard to the tension spring and its mounting. The spring 12¹ is a coiled tension spring which is wound under stress so that approximately the minimum tension desired in action is required to start the coils of the spring apart, springs wound with initial tension being well known.

A spring of this character has various 105 features which are advantageous for the use here described. Since the coils of the spring are practically in contact with each other at the beginning of movement of the generator towards the axle, it is obvious that less 110 space will be required to accommodate a given number of turns than would be required if it were necessary to stretch the coils apart to attain the initial tension. Also since the length of the spring when released 115 is only slightly less than its minimum length in action it is unnecessary to provide a screw for placing the spring under tension. Hence, it is possible to apply the spring by 120 swinging the generator a slight distance back of its normal maximum distance from the axle and dropping the spring in place, with a trunnion, or the like, at the lower end of the spring seated within suitable notches or seats on a bracket secured to the generator. As shown in Figs. 5 to 8 of the drawings, the upper end of the spring may be mounted by means of a hook 15 as previously described. The lower end of the 125 spring, however, is cut off without forming 130

any loop in the same, a trunnion member 26 being provided having a stem portion 27 which is provided with external screw threads of the same pitch as the spring, 5 this stem portion being adapted to be screwed into the lower end of the spring. This trunnion member is provided with cylindrical extensions 28, 28, transverse to the axis of the spring, these extensions being 10 adapted to rest against curved seats 29, which are formed on the bracket 19¹ secured to the generator, these seats facing downwardly. The spring is mounted in position by swinging back the generator, away from 15 the car axle, beyond its normal range of movement, until the extensions 28 of the trunnion can be slipped underneath the notches or seats 29. Thereafter extensions 28 of the trunnion member will be held in 20 position within seats 29 both by the weight of the generator and by the pull exerted by the belt on the generator pulley 8.

It will be noted that the construction described permits adjustment of the tension 25 spring 12¹ in accordance with whether the stem 27 of the trunnion member is screwed a greater or less distance into the convolutions of the spring before the spring is secured to the generator.

30 It should be understood that the invention is not limited strictly to the details of construction described but is as broad as is indicated by the accompanying claims.

What I claim is:

35 1. In a generator suspension, the combination of a car body, a generator adapted to be belt-driven from the car axle, a pivotal support for the generator beneath the car body, and a spring connected to said generator and car body, so arranged as to tend to swing the generator around its pivotal point away from the car axle, and so that its tension is in a substantial degree opposed to the weight of the generator.

40 45 2. In a generator suspension, the combination of a car body, a generator adapted to be belt-driven from the car axle, a pivotal support for the generator beneath the car body, from which the generator is suspended, and a spring extending downwardly at a steep angle from a connection with the car body above said pivotal support to a connection with said generator at the side thereof away from the car axle, said spring tending to swing the generator around its pivotal point away from the car axle, and a substantial component of the force of the spring acting upwardly, to reduce the load on said pivotal support.

50 55 60 65 3. In a generator suspension, the combination of a car body, a generator adapted to be belt-driven from the car axle, a pivotal support for the generator beneath the car, and a spring connected to said generator, so arranged as to tend to swing the gen-

erator around its pivotal point away from the car axle, said spring being wound under initial stress, so that approximately the minimum tension desired in operation is required to start the coils apart. 70

4. In a generator suspension, the combination of a support, a generator pivotally suspended thereupon and adapted to swing towards and away from an axle from which it is adapted to be driven, spring means 75 tending to swing said generator away from said axle, and a screw jack connected to said generator and adapted, when operated, to force said generator to swing towards said axle. 80

5. In a generator suspension, the combination of a support, a generator pivotally suspended thereupon and adapted to swing towards and away from an axle from which it is adapted to be driven, spring means tending to swing said generator away from said axle, a sleeve pivotally secured to said generator, and a screw threaded into said sleeve and having a bearing surface thereon adapted to contact against said support 90 when said screw is screwed outwardly of said sleeve, to force the generator to swing towards said axle. 85

6. In a generator suspension, the combination of a support having an opening therein, a generator pivotally suspended from said support and adapted to swing towards and away from an axle from which it is adapted to be driven, spring means tending to swing 95 said generator away from said axle, a sleeve pivotally secured to said generator, a screw threaded into said sleeve and having an extension extending into said opening, and a member on said screw adapted to act as a bearing to engage against the edge of said opening when said screw is screwed outwardly of said sleeve, to force the generator to swing 100 towards said axle. 105

7. In a generator suspension, the combination of a car body, a generator adapted to be belt-driven from the car axle, a pivotal support for the generator beneath the car body, a spiral spring tending to swing said generator around its pivotal point away 110 from the car axle, and connections between said car body and generator, including a threaded plug adapted to be screwed into the convolutions of the spring at one end thereof, said plug having trunnion portions 115 extending transversely to the threaded portion, and means providing seats in which said trunnion portions may be seated. 120

8. In a generator suspension, the combination of a car body, a generator adapted to be belt-driven from the car axle and having a bracket secured thereto on the side away from the axle, a pivotal support for the generator, secured to the car body, and a spring extending downwardly at a steep angle away from the car axle from a connec- 125 130

tion with the car body to said bracket adapted to swing the generator around its pivotal point away from the car axle, the arrangement being such that the effective lever arm to which the spring pull is applied decreases and the tension of the spring increases as the generator swings towards the axle.

9. The combination of a railway car, a generator pivotally supported beneath the car, a belt driving the generator from the car axle, and a spring tending to swing said generator about its pivotal support and tending to maintain the belt taut, said spring extending downwardly at an angle greater than 45° to the horizontal so that it removes the weight of the generator from its pivotal support to a substantial degree.

10. The combination of a railway car, a generator pivotally supported beneath the car, a belt driving the generator from the

car axle, and a spring tending to swing said generator about its pivotal support away from the axle and a pivotally mounted jack, 25 operation of which forces the generator toward the car axle to permit of easy placing of the belt in operative position.

11. The combination of a railway car, a generator pivotally supported beneath the car, a belt driving the generator from the car axle, and a spring tending to swing said generator about its pivotal support away from the car axle, and a screw jack carried with the generator and pivotally mounted 35 with respect thereto, operation of which forces the generator toward the car axle to permit of easy placing of the belt in operative position.

Signed at Depew, in the county of Erie 40 and State of New York, this 27th day of October A. D. 1921.

ELI J. BLAKE.
